UNITED STATES PATENT OFFICE.

MOSES ALBERT HARRIS, OF WESTFIELD, NEW JERSEY.

DESIGN FOR A REDUCTION-GEAR BASE.

55,467.

Specification for Design.

Patented June 15, 1920.

Application filed July 3, 1919. Serial No. 308,671. Term of patent 3½ years.

To all whom it may concern:

Be it known that I, MOSES ALBERT HARRIS, a citizen of the United States, residing at Westfield, in the county of Union and State of New Jersey, have invented a certain new, original, and ornamental Design for a Reduction-Gear Base, of which the following is a specification, reference being had to the accompanying drawing forming a part thereof.

Figure 1 is a plan view of the complete reduction gear base;

Fig. 2 is an end view of same; and

Fig. 3 is a side elevation.

I claim:

The ornamental design for a reduction gear base as shown.

MOSES ALBERT HARRIS.
